UNITED STATES PATENT OFFICE.

CLAËS G. SHEDIN, OF SOMERVILLE, MASSACHUSETTS.

MILLING-MACHINE.

SPECIFICATION forming part of Letters Patent No. 615,313, dated December 6, 1898.

Application filed August 9, 1898. Serial No. 688,173. (No model.)

To all whom it may concern:

Be it known that I, CLAËS G. SHEDIN, a citizen of the United States, residing at Somerville, in the county of Middlesex and State of Massachusetts, have invented new and useful Improvements in Milling-Machines, of which the following is a specification.

This invention relates to improvements in milling-machines; and it has for its object the milling of semicylindrical or oval surfaces, such as journal-bearings, &c., and it is carried out as follows, reference being had to the accompanying drawings, wherein—

Figure 1 represents a side elevation of a milling-machine provided with my improved attachment. Fig. 2 represents a front elevation of the same. Fig. 3 represents a detail side elevation of the pivoted links and attachment to the sliding work-support table. Fig. 4 represents a detail top plan view of said pivoted links, and Fig. 5 represents a cross-section on the line 5 5 shown in Fig. 2.

Similar letters refer to similar parts wherever they occur on the different parts of the drawings.

In the drawings, A represents the frame or standard of a well-known form of a milling-machine, on which B is the bracket, vertically adjustable in guides thereon.

C is the sliding work-supporting table movable in guides on the bracket B, as usual.

D represents the vise or clamp on the table C for holding the work S that is to be milled.

A' A" represent vertical uprights on the standard A, as usual.

A³ represents the horn or outer support for the milling-tool spindle.

E represents the rotary milling-tool-driving shaft, which is set in rotary motion by belt-power applied to its cone-pulley E', as is common in machines of this kind.

e represents the milling tool or cutter secured to the shaft E.

E" is a pulley secured to the rear end of the shaft E, from which leads a belt G to a pulley F" on the shaft F, to which is secured a cone-pulley F', from which leads a belt I to a cone-pulley H, secured to a shaft H', suitably journaled in bearings, and to the inner

end of said shaft is secured a bevel-gear h, the teeth of which mesh in a bevel-gear k, secured to a shaft K, journaled in suitable bear-

ings attached to the standard A, as shown. To the lower end of the shaft K is secured a bevel-gear k', adapted to intermesh intermittently with bevel-gears l and l', splined and longitudinally adjustable on the shaft L, as shown in Fig. 1.

L" is a lever for adjusting the gears l l' on the shaft L, so as to cause either one of said gears to be in gear with the bevel-gear k', according to the direction in which it is desired to rotate the shaft L.

To the forward end of the shaft L is secured a bevel-gear l", the teeth of which mesh in a similar bevel-gear b, which latter has its hub provided with a female screw-thread surrounding the vertical screw-threaded spindle B', the upper end of which is secured to the vertically-adjustable bracket B, as shown in Figs. 1 and 2.

On one side of the frame of the machine are arranged guides A⁴, in which the inner ends O' P' of the respective links O P are guided for a purpose, as will hereinafter be more fully described.

To one side of the frame of the machine is secured or made integral therewith a plate A⁵, provided with vertical guides a⁵ a⁵, in which is vertically adjustable the plate M, which is preferably adjustable by means of a screw m. (Shown in Fig. 2.)

On the plate M is pivoted at n a guide-bar N, adapted to be secured at its upper end to the plate M, preferably by means of a fastening-screw n' or other similar device.

m' m' are screw-threaded perforations in the plate M for the purpose of securing the guide-bar N in any desired position on the plate M, according to the curvature that is to be made on the articles to be milled.

n" is a suitable handle on the guide-bar N for the operator to take hold of when adjusting the position of said guide-bar on the said plate M.

O and P represent links having their inner ends O' P' adapted to move up and down in the guide A⁴, as shown. Said links are pivoted together and to a pin or bolt Q, passing through an ear or projection on the work-supporting table C, as shown in Fig. 2.

The link O is provided with an extension O", to the free end of which is pivoted at O³ a cross-head R, provided at its ends with anti-

friction-rollers r r , adapted to roll against opposite sides of the guide-bar N during the vertical and horizontal movement of the work-support C.

5 The guide N during the vertical adjustment of the work-supporting plate C serves to impart a horizontal movement to the latter, causing thereby the piece S to be moved in a curved path relative to the rotary milling-tool e, thus causing the latter to cut or mill the article operated on in the desired curvature, circular or otherwise, as may be desired, according to the position of the guide-bar N on the plate M.

15 By adjusting the plate M up or down on the stationary plate or bracket A⁵ articles of various sizes or diameters may be milled, as may be desired.

20 By adjusting the position of the bar N on the plate M any desired curvature may be produced on the article acted upon by the rotary milling-tool.

25 In using this my improved milling-machine the article S to be milled is secured in the vise D upon the table C after the plate M has been adjusted on the bracket A⁵, according to the size of the article to be milled. The position of the bar N is then adjusted on the plate M, according to the curvature, 30 semicylindrical or otherwise, that is to be given to the article that is being milled. Rotary motion is then imparted to the milling-tool or cutter e in the usual manner. By moving and securing the lever L'' in the position shown in Fig. 1 the bevel-gear l is put in gear with the bevel-gear k'. By the rotation of the pulley H a rotary motion is imparted to the shaft L, causing the screw-threaded gear b to move the bracket B, its 35 table C, and work S, secured thereon, downward, as shown by the arrow in Fig. 2, and during such downward movement of the work-support C it is simultaneously caused to move sidewise in the direction of the arrow shown 40 upon it in Fig. 2 by the influence of the guide- 45

bar N, rollers r r, and intermediate connecting mechanism between said rollers and the table C, causing the latter and the article S, secured to it, to move in a circular or curved path until the cutter or milling-tool e reaches the highest part of the article that is being milled, when the operator first swings the lever N to the position shown in dotted lines in Fig. 2 and secures it in such position and reverses the rotary motion of the shaft L by 50 swinging the lever L'' to the position shown in dotted lines in Fig. 1, by which the gear l' is put in gear with the bevel-gear k' and the gear l disconnected therefrom, causing the rotary motion of the shaft L to be reversed, 55 and consequently causing the bracket B, table C, and work S to be gradually moved upward and the table C and the work S secured thereto to be moved in the same direction as before, causing the other half of the article to be milled and shaped to the desired curvature.

60 Having thus fully described the nature, construction, and operation of my invention, I wish to secure by Letters Patent and claim— 70

75 In a milling-machine, in combination, a rotary milling-tool, a frame or standard, a bracket vertically adjustable thereon, a work-support laterally sliding on said bracket, a stationary frame extension A⁵, a plate M vertically adjustable on the latter, a lever N pivotally adjustable on said plate M, a pair of levers O, O', P pivoted together and to the work-support, said levers being guided on the guide-bar N during the up-and-down 80 motion of the bracket and the horizontal motion of the work-support, substantially as and for the purpose set forth.

85 In testimony whereof I have hereunto set my hand in presence of two subscribing witnesses.

CLAES G. SHEDIN.
